UNITED STATES PATENT OFFICE.

JACOB K. GRIFFITH, OF PITTSTON, PENNSYLVANIA, ASSIGNOR TO A. J. GRIFFITH, OF PITTSTON, PENNSYLVANIA.

GRINDING-MILL.

1,295,482.

Specification of Letters Patent. Patented Feb. 25, 1919.

Application filed April 18, 1916. Serial No. 91,924.

To all whom it may concern:

Be it known that I, JACOB K. GRIFFITH, a citizen of the United States, residing at Pittston, in the county of Luzerne and State of Pennsylvania, have invented a new and useful Improvement in Grinding-Mills, of which the following is a full, clear, and exact description, reference being had to the accompanying drawings, forming part of this specification, in which:

Figures 1, 2, 3, 4 and 5 are diagrams illustrating positions which may be assumed by one form of grinding units embodying my invention.

15 Figs. 6 and 7 are sectional views taken in planes at right angles to each other, illustrating another form of my invention.

Fig. 8 is a cross sectional view of the tube mill showing another form of the invention.

20 Fig. 9 is a sectional view on the line IX-IX of Fig. 8.

Fig. 10 is a view partly in side elevation and partly in section of one of the units shown in Figs. 8 and 9.

25 Figs. 11, 12 and 13 are diagrams illustrating the advantages of my invention.

Figs. 14 and 15 are comparative diagrams further illustrating such advantages.

My invention has relation to improvements in mills for the grinding of cement, or ores of the precious metals for concentration, flotation, cyanidation and amalgamation; or to other grinding mills in which it is desirable to grind the material finer and at less cost than in the mills at present used.

For many years the fine grinding of cement clinkers has been largely carried out by the use of so called tube mills, in which 40 quartz pebbles were used as grinding elements. More recently these quartz or flint pebbles have been replaced to a large extent by the use of steel slugs and balls. By the use of balls of 1" diameter the output has 45 been increased about 25 per cent. due to the increase in the points of contact as well as to the increase in the weight of the balls over that of pebbles. By the use of slugs (which are chilled iron or steel cylinders of 50 about one inch in diameter by one and one-half inches long) a still larger area of grinding surface is obtained, this enabling the

output to be increased about 40 per cent. over that with flint pebbles. The use of ball-mills for grinding ore has been adopted 55 from the cement industry.

My invention is designed to provide grinding units or elements in which the area of contact, as well as the efficiency of action due to increased weight and other causes, is 60 so arranged that the resulting output of the mill is very greatly increased.

To this end, my invention consists in the use of grinding elements or units of multiple-ball forms.

Referring first to that form of my invention shown in Figs. 1 to 5, inclusive, and in Fig. 14, each grinding element consists of what may be termed double or twin balls. That is to say, each element consists of two 70 ball-shaped end portions 2, connected by an intermediate portion 3 of reduced diameter. The weight and size of these units can be fixed at will. In use, they may be placed in any type of mill of this general class, and 75 the mill operated in the same manner as with the pebbles, balls or slugs at present in use.

The advantages of this form of my invention as compared with the original ball elements will be more apparent by a comparison of Figs. 14 and 15. When balls are employed, such as illustrated in Fig. 15, assuming that a ball is 1" in diameter and is surrounded by other balls of the same size, it 85 will require 12 balls to surround it on all sides, and as these balls only touch the center ball at 12 points, the complete group will have 14 interstices.

In accordance with my invention, the 18 90 balls shown in Fig. 15 would be replaced by 9 of the twin balls shown in Fig. 14, giving only 8 interstices compared with 20 interstices shown in Fig. 15, or 60 per cent. less.

The greater area of contact between the 95 elements obtained by my invention will also be apparent from Figs. 11, 12 and 13.

In Fig. 11, I have shown double balls such as would be formed by uniting two balls which would touch each other if not united. 100 In this case the arc of contact is 60° of a circle, or .785" long with a ball of 1½" in diameter. When the double balls touch each other longitudinally, the line of contact is

1.57" in length. Fig. 12 shows double balls formed by uniting two single balls, which if not united would be $\frac{1}{2}$ " apart. In this form, the arc of contact is 72° , or .94" in length; and when assembled longitudinally, the line of contact is 1.88" in length.

Fig. 13 shows a similar arrangement except that the two balls if not united would be separated by $\frac{1}{2}$ ". This increases the arc of contact 85° , or to 1.15" in length and increases the longitudinal line of contact to 2.3" in length. This line of contact is .73" longer or 32 per cent. more than that shown in Fig. 11. The arrangement shown in Fig. 11 gives an efficiency of about 60 per cent. greater than that of single balls and the efficiency of the arrangement shown in Fig. 13 is about 92 per cent. greater than that resulting from the use of single balls.

A further advantage of my invention results from the fact that when the double balls are assembled they are in such relation to each other that they cannot be easily separated while under pressure. The material being ground is, therefore, confined much more closely and is ground much more finely than with the usual pebbles, balls or slugs. Furthermore, inasmuch as the circumference of the end portions 2 of the balls is considerably greater than the circumference of the central portion 3, when the balls are in contact and revolving, the end portions have a very much greater surface velocity than that of the central portions. This produces a disintegrating action which is somewhat similar in its nature to the grinding effect produced by the old fashioned mill stones. This is an important feature which greatly increases the grinding efficiency. A still further unique feature of the invention is that the more the units become worn, the greater is their efficiency, since wear results in increasing their contact areas.

In use, the elements or units may assume an almost kaleidoscopic number of different positions, some of which I have illustrated in Figs. 1 to 5. These, of course, are illustrative only.

Instead of employing double ball units or elements, I may employ elements having three or more lobes or ball portions; and in fact the elements may take the form of loose rolls, as shown in Figs. 6 to 10, inclusive.

In the forms shown in Figs. 6 and 7, I have shown rolls consisting of a number of sections 4 strung end to end on a central rod 5.

These sections may be of varying lengths, as shown, each having one or more ball portions. Elements of this form are placed loosely in the tube mill, as indicated in Figs. 6 and 8. With this form, I prefer to cor-

rugate the lining 6 of the tube mill circumferentially, as indicated at 7, these corrugations being adapted to the form of the ball portions of the grinding elements. If desired, the lining of the mill may also be corrugated longitudinally, as shown at 8 in Fig. 8.

Instead of making the units in a number of separate sections, as shown in Fig. 7, they may be cast of the desired length, in a single piece, as shown at 9 in Figs. 8, 9 and 10.

By the use of these elements, the grinding is produced not only by their weight and revolving action, but by the V-shaped ball portions of one element forcing their way in the grooves of the same shape in the adjacent elements and in the lining plates of the mill. In short tube mills, these grinding elements could be made very heavy so as to occupy a large portion of the inside diameter of the mill.

In the grinding of cement, which contains but a small amount of silica, the abrasion or wear is so slight that the connecting portion 3 of a double ball, or the small diameter portions of a multiple ball, may be made quite small, and as already explained the difference in the diameter of the end and central portions has an important effect upon the disintegrating action, and the greater the difference in this diameter, the greater is the disintegrating effect. With elements of relatively large diameter, this proportion of difference can be increased.

The elements may be made of any metal best suited to the work they are to be used for, such as chilled cast iron, high carbon steel, oil tempered, or any suitable alloy. They may be either rolled or cast.

The advantages of my invention in improving the efficiency of this class of mills will be readily apparent to those skilled in this art.

110

I claim:

1. The combination with a comminuting mill of a plurality of grinding bodies therein free to move in any direction with relation to each other and of a general dumb-bell shape having rounded or convex end portions and a reduced rounded neck portion connecting the convex end portions, and forming a saddle-shaped surface which is adapted for co-action with the convex surface of the end portion of another body, substantially as described.

2. The combination with a comminuting mill, of a plurality of tumbling grinding bodies therein, free to move in any direction with relation to each other and of a general dumb-bell shape, having substantially spherical ball-like end portions and a reduced round neck portion connecting the end portions and forming a saddle-shaped

115

120

125

130

surface having a reëntrant curvature approximately equal to the curvature of the end portions, so that the neck portion of one body is adapted to conform to and coact with the end portion of another body.

3. A grinding body for use in a tumbling mill having a general dumb-bell shape, having rounded or convex end portions and a reduced rounded neck portion connecting the end portions and having a reëntrant curvature of substantially the same radius as the curvature of the end portions and adapted to co-act with the end portion of another and similar body so as to have continuous surface contact therewith, substantially as described.

4. The combination with a comminuting mill of a tumbling grinding body, free to move in any direction therein and of a general dumb-bell shape, having rounded or convex end portions and a reduced rounded neck portion connecting the convex end portions, and a second tumbling grinding body also free to move in any direction therein and of a general dumb-bell shape having rounded or convex end portions and a reduced rounded neck portion connecting the convex end portions, the neck portion of one body being adapted to conform to and co-act with the end portion of the other body, substantially as described.

5. A tube mill having internal circumferential corrugations and a plurality of loose grinding elements having enlarged portions and intermediate connecting portions of less diameter and of a surface contour fitting the corrugations of the mill

and fitting the other grinding elements, substantially as described.

6. A tube mill having internal circumferential corrugations, a plurality of loose grinding elements having approximately spherical portions and intermediate connecting portions of less diameter than the spherical portions and of a surface contour fitting the corrugations of the mill and fitting the other grinding elements, substantially as described.

7. A tube mill having internal circumferential corrugations, a plurality of loose grinding elements having approximately spherical portions and intermediate connecting portions of less diameter than the spherical portions and of a surface contour to adapt them to fit the corrugations of the mill and to fit the other grinding elements, said mill also having longitudinal corrugations, substantially as described.

8. A grinding element or unit comprising a body of general dumbbell shape having rounded or convex end portions and a reduced concave rounded neck portion connecting the convex end portions and forming a saddle-shaped surface which is adapted for coaction with the convex end surfaces of other similar units, substantially as described.

In testimony whereof, I have hereunto set my hand.

JACOB K. GRIFFITH.
